CLAIM

The ornamental design for a joint former as shown and described.

DESCRIPTION

This application is related to the following commonly owned co-pending patent application: U.S. application Ser. No. 18/463,426, entitled “Apparatus for Forming a Pathway Joint.”

FIG. 1 is a top perspective view of a joint former of one embodiment of my new design.

FIG. 2 is a top view of the joint former of FIG. 1.

FIG. 3 is a bottom view of the joint former of FIG. 1.

FIG. 4 is a front view of the joint former of FIG. 1.

FIG. 5 is a rear view of the joint former of FIG. 1.

FIG. 6 is a left side view of the joint former of FIG. 1, the right side view being a mirror image thereof.

FIG. 7 is a top perspective view of a joint former of another embodiment of my new design.

FIG. 8 is a top view of the joint former of FIG. 7.

FIG. 9 is a bottom view of the joint former of FIG. 7.

FIG. 10 is a front view of the joint former of FIG. 7.

FIG. 11 is a rear view of the joint former of FIG. 7; and, FIG. 12 is a left side view of the joint former of FIG. 7, the right side view being a mirror image thereof.

The drawings contain symbolic break lines in FIG. 1-5. The break lines and the portions of the article between the break lines forms no part of the claimed design.
